BURIAL VAULT

James Leo Halley, San Francisco, Calif.
Application October 10, 1955, Serial No. 539,587
7 Claims. (Cl. 27—35)

This invention relates to improved receptacles or burial vaults for containing human corpses.

In my Patent No. 2,705,828 issued April 12, 1955, I disclosed a receptacle for containing a human corpse that allows the fluid released by the decomposition of a corpse to drain from the receptacle and after complete decomposition permits the drain outlet from the receptacle to be sealed.

It is, in general, the broad object of the present invention to provide an improved casket or vault construction that can be sealed from within the receptacle or vault itself.

Another object of the invention is to provide a unitary receptacle or vault that includes within its structure its own aseptic or septic tank so that fluid emitting from the vault during decomposition of the corpse can be purified and thus will not be odoriferous or contaminating and can be, if desired, discharged into a sewer system.

A further object of the present invention is to provide receptacles or vaults that are capable of use either in a grave or in a mausoleum where multiple burials are contemplated, and wherein after decomposition of the corpses in each vault, the vaults can be separately sealed.

It has been the custom to enclose a body in a casket which may or may not be hermetically sealed, then on burial in the ground this casket is lowered into a cement or wooden vault that is previously placed in the ground. It is known that the human body is composed of approximately 85% water or liquid and to this is added the embalming fluid. Therefore, when a corpse decomposes, a quantity of fluid is released. If the casket is hermetically sealed and is water impervious, the corpse continues to lie in this putrid fluid, and in the event of disinterment of the body, for any reason, persons disinterring the corpse are subject to offensive, putrid, unsightly and unsanitary conditions. If the casket is not water impervious, the cement or wooden vault into which the casket is placed along with the casket becomes saturated with the putrid fluid released as a result of decomposition of the corpse, and disinterment is a nasty, odoriferous and distasteful task.

The present invention alleviates any such condition because the liquid or fluid released by the decomposition and dehydration of the corpse is immediately drained from the compartment in the vault wherein the corpse is located and is channeled into an aseptic or septic compartment wherein said fluid can be treated to purify the same and then is permitted to flow into the ground or into a regular sewer drain, if one is available. An odor test can be made from time to time to determine when decomposition and dehydration of the body is complete. When the body has completely decomposed and dehydrated, then the vault itself can be permanently and hermetically sealed from within. Also by use of the present invention, multiple burials can be made in the same grave or in a mausoleum and the second or third vault can be easily connected to the septic or aseptic compartment of the first vault.

One form which the invention may assume is exemplified in the following description and illustrated by way of example in the accompanying drawings, in which:

Fig. 1 is an end view in elevation showing two vaults in use with the vent pipes and drains of the two vaults shown.

Fig. 2 is a side view taken along line 2—2 of Fig. 1, showing the two vaults in use with the vent pipe and drain of the lower vault shown.

2

Fig. 3 is a side view taken along line 3—3 of Fig. 1, showing the two vaults in use with the vent pipe and drain of the upper vault shown.

Fig. 4 is a fragmentary view taken along line 4—4 of Fig. 3.

Fig. 5 is a fragmentary view taken along line 5—5 of Fig. 3.

Fig. 6 is a perspective view of the two vaults showing the arrangement of the drain pipes.

Referring to the accompanying drawings, wherein similar reference characters designate similar parts throughout, Fig. 1 shows a multiple burial wherein two vaults are employed, each containing a human corpse. The vaults are constructed of water-impervious material such as concrete or like substance. The lower or bottom vault is generally indicated at 10 and the upper or top vault is generally indicated at 11. The lower vault has side walls 12, end walls 13 and 14, a cover 15, an intermediate bottom wall 16 and a bottom wall 17. At one end of said intermediate bottom wall 16 there is formed a sump 18. Said sump is generally of rectangular shape and has an angularly disposed end wall, indicated at 19. The end wall 19 is angularly disposed to facilitate the filling of the sump 18 with a settleable material, as will be herein-after explained. A drain outlet 20 is formed in the bottom of said sump 18, said drain outlet preferably having a threaded screen 21 at the upper end thereof that is disposed above the floor of the sump to prevent the blocking or clogging of the drain by any loose, solid or semi-solid matter within the vault. A ball float 22 is placed within the drain outlet, and said ball float is inserted within the drain outlet by unscrewing the screen 21 and dropping the ball float 22 in said drain. The ball is held in place in said drain by a pin 23 that is affixed to the side of the drain and prevents the ball from dropping completely through the said drain outlet. If, by any chance, the water level of the surrounding ground in which the vault is buried should rise to such an extent, and water should back up into said drain, said ball float would seat itself on the valve seat 24 and close said drain outlet 20.

Channels 25 are formed in the upper surface 26 of said intermediate bottom wall 16 to direct the flow of fluid into the sump 18 and drain outlet 20. The said drain outlet connects at its lower end with a septic or aseptic drain compartment 27 formed in the bottom of the vault by the intermediate bottom wall 16, bottom wall 17, and the lower portion of the end wall 13 and wall 28. Bottom wall 17 slopes slightly downwardly away from wall 13 to facilitate the drainage of fluid from said drain compartment 27. Fluid passing through compartment 27 can be purified by any well-known method of purification. Wall 28 has an outlet 29 to permit the drainage of fluid from said compartment 27. A hinged valve 30 covers the outlet 29. This valve prohibits underground animals or insects from entering the compartment 27, and also in the event the water level should at any time rise to above the level of the valve, it acts to prevent the water from backing up into compartment 27. In the event burial is to be in a mausoleum, the outlet 29 can be threaded and connected directly to sewer facilities. An air space 31 is provided at the rear of the valve 30 so that said valve can at all times operate freely and fluid can easily drain from said compartment 27 through said outlet 29 and valve 30. A screen 32 is placed over the open end of said air space 31 to stop bugs, insects, rodents or dirt from entering said outlet and valve.

The end wall 13 of said vault has included therein pipes or conduits 33 and 34. Conduit 33 passes through end wall 13 with its lower outlet 35 terminating in a recess 36 at one end of the sump 18 and the upper lip 35a of said outlet being below the upper surface 26 of the intermediate bottom wall 16. The upper end of said conduit

33 attaches by nipple connection 37 to conduit 38 that extends upwardly to ground level. The upper end of said conduit 38 is closed by a threaded cap. Placed in said conduits 33 and 38 is a bleeder pipe 39, the use of which will be explained in detail hereafter.

In the event of a single burial, wherein only the lower vault 10 is employed, said vault is lowered into a grave dug in the ground or is placed in a mausoleum. The casket containing the corpse is then placed in said vault and the cover 15 is sealed in place. The conduit 38 is screwed into the nipple 37 and a threaded cap is placed over said conduit 38. From time to time an odor test can be made by unscrewing the said threaded cap. When it is determined by the odor test that the corpse is completely decomposed and dehydrated, then the threaded cap can be removed and a sealing material can be poured down conduits 38 and 33, filling the sump 18. Any pressure of air formed in the vault, caused by the introduction of a sealing material into the vault, can pass out through the bleeder pipe 39. A sufficient amount of sealing material is poured into the vault to completely seal conduit 33 and bleeder pipe 39. The construction of the sump 18 facilitates the complete sealing of the vault due to the fact that the upper lip 35a of conduit 33 opens into said sump so that it is below the upper surface 26 of the intermediate horizontal wall 16. Also the angularly disposed end wall 19 of the sump tends to force the settable material back upon itself to completely fill said sump 18. The vault then becomes hermetically sealed and if the body is later exhumed for any purpose, there is no unpleasant odor or mess to contend with. This is also true if the body must be exhumed before complete decomposition and dehydration because all of the fluid formed by the partial decomposition and dehydration of the body is drained from the vault as it is formed. In the ordinary burial, particularly where a waterproof hermetically sealed vault is employed, on exhumation a foul and disagreeable condition is encountered because the fluids occasioned by decomposition stay in the casket or vault and make such a task practically unbearable.

When two or more burials are contemplated in the same grave or mausoleum, additional conduits, such as conduit 34, are placed in the end wall 13 of the vault 10 as shown in Fig. 1. These conduits also terminate at their lower end in the compartment 27 and at their other end at the upper end of wall 13. When not in use, they are capped over in the usual manner. The second vault 11 has side walls 40, end walls 41 and 42, cover 43 and bottom 44.

The bottom 44 of the second vault has formed therein a sump 45 with a drain outlet 46, floating ball valve 47 and valve seat 48 similar to that in the first vault. One wall of said sump 45 is formed at an angle, as indicated at 49. This is so formed to facilitate the closing of the vault with a settable material, as previously described. Channels 50 are also formed in the said bottom 44 for drainage purposes.

The end wall 41 has an offset 51 formed therein. In said offset is a conduit 52. The lower end of said conduit 52 connects with sump 45, and the upper end of said conduit 52 is connected to a vent pipe 53. Said vent pipe 53 is closed at its upper end by a threaded cap 54. The end wall 41 is formed so that its lower face 55 is approximately parallel to the upper face of the bottom 44 and is below the lower end 52a of conduit 52. By this construction, said sump 45 includes two walls that are capable of blocking any sealing material poured therein; namely, the angular wall 49 and wall 56 formed by the lower portion of end wall 41. The said drain outlet 46 is constructed similarly to drain outlet 20 with a threaded screen 57, float ball valve 47 and valve seat 48. Said drain outlet 46 is connected to conduit 34 in end wall 13 of the said first vault 10 which connects with compartment 27 of the said first vault 10. Any

standard type connection is employed to join the drain outlet 46 to conduit 34.

Fluid released as a result of decomposition of the body in the second vault will flow along channels 50 into the sump 45, out drain 46 through conduit 34 and into drain compartment 27, and finally through drain 29.

When multiple burials are contemplated, the cover 15 of the first vault 10 has formed therein two recesses 58 and 59 and the bottom 44 of the second vault 11 has formed therein recesses 60 and 61. These two sets of recesses 58-59 and 60-61 are in alignment. On the first burial, dummy half pins are inserted in recesses 58 and 59. However, in the event of a second burial these dummy pins are removed and pins 62 and 63 are inserted in said recesses 58 and 59, and when the second vault is lowered into position, the upper ends of said pins 62 and 63 are inserted in recesses 60 and 61, respectively. The second or top vault 11 is held in place on the first vault not only by the connection of the drain outlet 46 with the conduit 34, but also by the pins 62 and 63.

After the second burial, an odor test can be made from time to time to determine the state of decomposition and dehydration of said second corpse and when, as a result of such test, it is determined that decomposition and dehydration has been completed, a sealing material may be poured down vent pipe 53 and conduit 52 into the sump 45. A sufficient amount of sealing material is poured into the said sump 45 to completely fill the same, thus covering the drain outlet 46, closing the lower end of conduit 52 and sealing said vault 11. Any air put under pressure by the introduction of the sealing material can pass out of said vault through the bleeder pipe 64. By this means the pouring of the sealing material into the vault is greatly facilitated as no back pressure is built up thereby.

Additional burials can be made using the drain compartment 27 by merely placing in the end wall 13 of vault 10 additional conduits so that drains from additional vaults can be connected therewith.

By the use of this construction sanitary conditions are greatly improved, for not only is the corpse permitted to dehydrate as a result of decomposition, but the fluid released by such decomposition of the body can be purified to a great degree by passage through the drain compartment wherein said fluid is treated by any well-known method of purification. Thus, any fluid flowing out of the vault is free from contamination.

While I have shown the preferred form of my invention, it is to be understood that various changes may be made in its construction by those skilled in the art without departing from the spirit of the invention as defined in the appended claims.

Having thus described my invention, what I claim and desire to secure by Letters Patent is:

1. A burial vault for receiving a human corpse, said vault comprising integral vertical side and end walls, an intermediate bottom wall, a bottom wall, a cover at the upper ends of the vertical walls to close said vault, said side and end walls, cover, intermediate wall and bottom wall forming a corpse receiving chamber and a drain compartment underlying the chamber, said intermediate wall being formed with a drain passageway communicating between the said corpse receiving chamber and said drain compartment, a conduit connected at its lower end to the drain compartment adjacent said drain passageway and terminating at its upper end adjacent the top of said vault whereby sealing material may be introduced through the conduit to seal it and the drain passageway.

2. A burial vault for receiving a human corpse, said vault comprising monolithic integral vertical side and end walls, an intermediate horizontal bottom wall, a horizontal bottom wall, a monolithic cover at the upper ends of the vertical walls to be hermetically sealed relative thereto, said side and end walls, cover, intermediate wall and bottom wall forming a corpse receiving chamber and a

drain compartment underlying the chamber, said intermediate wall formed with a sump adjacent one end thereof, a drain passageway communicating between the sump and said drain compartment, a conduit formed in one end wall and opening at its upper end through the top thereof and at its lower end in the sump adjacent the bottom thereof whereby sealing material may be introduced through the conduit to seal said conduit, sump and the drain passageway.

3. A burial vault for receiving a human corpse, said vault comprising monolithic integral vertical side and end walls, an intermediate horizontal bottom wall, a horizontal bottom wall, a monolithic cover at the upper ends of the vertical walls to be hermetically sealed relative thereto, said side and end walls, cover, intermediate wall and bottom wall forming a corpse receiving chamber and a drain compartment underlying the chamber, said intermediate wall formed with a sump adjacent one end thereof, a drain passageway communicating between the sump and said drain compartment, valve means in said drain passageway to permit fluid flow from the sump to the compartment only, a conduit formed in one end wall and opening at its upper end through the top thereof and at its lower end in the sump adjacent the bottom thereof whereby sealing material may be introduced through the conduit to seal said conduit, sump and the drain passageway.

4. A burial vault for receiving a human corpse, said vault comprising monolithic integral vertical side and end walls, an intermediate horizontal bottom wall, a horizontal bottom wall, a monolithic cover at the upper ends of the vertical walls to be hermetically sealed relative thereto, said side and end walls, cover, intermediate wall and bottom wall forming a corpse receiving chamber and a drain compartment underlying the chamber, said intermediate wall formed with a sump adjacent one end thereof, a drain passageway communicating between the sump and said drain compartment, valve means in said drain passageway to permit fluid flow from the sump to the compartment only, a conduit formed in one end wall and opening at its upper end through the top thereof and at its lower end in the sump adjacent the bottom thereof whereby sealing material may be introduced through the conduit to seal said conduit, sump and the drain passageway, and one wall of the drain compartment being formed with a drain opening for permitting fluid to drain from said compartment.

5. Multiple burial vaults for receiving human corpses comprising a first vault formed of integral vertical side and end walls, an intermediate bottom wall, a bottom wall, a cover at the upper ends of the vertical walls, said side and end walls, cover, intermediate wall and bottom wall forming a corpse receiving chamber and a drain compartment underlying said chamber, said intermediate wall being formed with a drain passageway communicating between the said corpse receiving chamber and said drain compartment, a first conduit terminating at its lower end in the chamber adjacent said drain passageway and its upper end above the top of said first vault whereby sealing material may be introduced through said first conduit to seal it and said drain passageway, a second conduit spaced laterally from said first conduit and terminating at its lower end in said drain compartment and extending upwardly to the top of said first vault, a second vault for receiving a human corpse formed of integral side and end walls, a bottom wall and a cover forming a corpse receiving chamber, said second vault being adapted to be superimposed on the first vault, a drain passageway communicating between the said corpse receiving chamber and said second conduit, a third conduit terminating at its lower end adjacent the drain passageway of said second vault and at its upper end above the top of said second vault whereby sealing material may be introduced through said third conduit to seal it and said drain passageway in said second vault.

6. Multiple burial vaults for receiving human corpses comprising a first vault formed of integral vertical side and end walls, an intermediate bottom wall, a bottom wall, a cover at the upper ends of the vertical walls, said side and end walls, cover, intermediate wall and bottom wall forming a corpse receiving chamber and a drain compartment underlying said chamber, said intermediate wall being formed with a sump adjacent one end thereof, a drain passageway communicating between the said sump and said drain compartment, a first conduit terminating at its lower end in the sump adjacent the bottom thereof and at its upper end above the top of said first vault whereby sealing material may be introduced through said first conduit to seal said conduit, sump and said drain passageway, a second conduit spaced laterally from said first conduit and terminating at its lower end in said drain compartment and extending upwardly to the top of said first vault, a second vault for receiving a human corpse formed of integral side and end walls, a bottom wall and a cover forming a corpse receiving chamber, said second vault being adapted to be superimposed on the first vault, said second vault being interiorly formed with a sump, a drain passageway communicating with the said sump and said second conduit, a third conduit terminating at its lower end adjacent the sump of said second vault and at its upper end above the top of said second vault whereby sealing material may be introduced through said third conduit to seal said conduit, sump and drain passageway in said second vault.

7. Multiple burial vaults to be disposed beneath the ground for receiving human corpses comprising a first vault formed of monolithic integral vertical side and end walls, an intermediate horizontal bottom wall and a horizontal bottom wall, a monolithic cover at the upper ends of the vertical walls to be hermetically sealed relative thereto, said side and end walls, cover, intermediate wall and bottom wall forming a corpse receiving chamber and a drain compartment underlying said chamber, said intermediate wall being formed with a sump adjacent one end thereof to receive fluid from said chamber, said intermediate wall being formed with a drain passage forming a communication between said sump and said compartment, a float valve member and seat in said drain passage to permit flow from the chamber to the compartment only, a first conduit formed in one end wall and opening at its upper end at the top end of said wall and at its lower end in the chamber in communication with the sump whereby sealing material may be introduced through said first conduit to seal it and said drain passageway, said one end wall being formed with a second conduit extending between the upper end of the wall and said drain compartment and spaced laterally from the first conduit, a second vault for receiving a human corpse formed of monolithic integral vertical side and end walls, a bottom wall and a cover forming a corpse receiving chamber, said second vault being adapted to be superimposed on the first vault, said second vault being interiorly formed with a sump communicating with said chamber and extending into one end wall, the bottom wall of said second vault being formed with a drain opening therethrough adapted to register with said second conduit in the end wall of the first vault when the second vault is superimposed thereon, valve means in said drain opening permitting only downward flow of fluid from said chamber and sump to said second conduit, said end wall of said second vault being formed with a vertical passageway therethrough and extending from the sump through the top of the wall.
